DRAPE

Edith Rodriguez, Washington, D.C. (P.O. Box 292, Contant 72, St. Thomas, U.S. Virgin Islands)

Filed Oct. 19, 1970, Ser. No. 25,548

Term of patent 7 years

Int. Cl. D6—10

U.S. Cl. D47—6

FIG. 1

FIG. 2

FIG. 1 is a front elevational view of drapes showing my new design; and

FIG. 2 is an enlarged fragmentary view thereof.

I claim:

The ornamental design for drapes, substantially as shown.
